PERIODIC VOLTAGE GENERATOR

Madison Cawein, Manhasset, N. Y., assignor to
Hazeltine Corporation, a corporation of Delaware

Application February 15, 1936, Serial No. 64,022

12 Claims. (Cl. 250—36)

This invention relates to the generation of periodic voltages of complex wave form, such as "saw-tooth" and related forms, and to the utilization of such voltages, particularly for effecting cathode-ray scanning in television systems.

According to present practice in television systems, a carrier wave is transmitted, modulated by picture or video-frequency signals, corresponding to the varying values of light and shade in the transmitted picture. Scanning synchronizing impulses are also transmitted, usually also as modulation frequencies impressed on the same television carrier as the video frequencies. A cathode-ray tube is employed at the receiver, where in a cathode ray or electron beam is produced and focused upon a fluorescent screen. Voltages at video frequencies, derived from the received carrier, are utilized to vary the intensity of the ray according to the signal amplitude. In order to effect scanning of the screen by the ray, saw-tooth voltage or current waves are generated and utilized at the receiver to produce, respectively, electrostatic or magnetic fields of saw-tooth wave form which deflect the cathode ray, usually horizontally for line scanning and vertically for picture scanning. The well-known rectilinear pattern is thereby traced upon the screen to reproduce the scene. The synchronizing impulses derived from the carrier are utilized to control or operate the scanning wave generators so that the scanning actions at the receiver are maintained in proper synchronism with the corresponding actions at the transmitter.

In present practice, relatively high voltages are employed for the electrodes of the cathode-ray tube, as for focusing the ray, and correspondingly high scanning voltages are, therefore, required. It is, of course, essential that the saw-tooth scanning voltages be of such wave form as to effect accurate linearity of trace and rapid retrace of the scanning ray. Furthermore, it is highly desirable that the scanning voltage generators be relatively simple in their construction and operation.

Because of inherent electrostatic and magnetic disturbances to which the deflecting plates of a cathode-ray tube are subjected in operation, it is desirable, if not necessary, that these plates be electrically balanced with respect to ground, thereby to neutralize the effects of the disturbances (which will then occur simultaneously and in the same polarity on the opposite plates). With the plates so balanced with respect to ground, the deflecting voltages applied thereto should also be balanced relative to ground, that

is, applied to the plates with equal amplitudes and opposite polarities, if maximum efficiency is to be obtained. More particularly, by utilizing two balanced deflecting voltages only one-half of the voltage amplitude is required for each half of the scanning voltage supply, as in the case where a single unbalanced scanning voltage is used, and hence an operating voltage may be used for the generator which is of an amplitude of only one-half that which would be needed if a single unbalanced scanning voltage were to be developed. Furthermore, any electrostatic and magnetic disturbances to which the voltage supply circuits are subjected will be balanced out or neutralized in these circuits also, when such a balanced arrangement is employed.

It is an object of the present invention to provide an improved generator for developing periodic voltages which are of balanced, and preferably of saw-tooth, wave form, which are of relatively high amplitudes, and which are especially suitable for use in a television receiver to effect scanning by the cathode ray.

A further object of this invention is to provide a generator of the character described, which is relatively simple in its construction and operation.

In accordance with the present invention, there is provided a periodic voltage generator which includes capacitance means, as for example a condenser, and a source of direct current. A pair of circuits is provided for charging the capacitance means to opposite polarities from the direct-current source, and means are provided for controlling the circuits, periodically to charge the capacitance means alternately to opposite polarities. One of the circuits includes two impedance means of substantially equal values and symmetrically disposed in the circuit for the periodic current therein. The term "symmetrically disposed" as used in this specification and in the appended claims is intended to denote the relationship whereby corresponding portions of the elements, in connection with which the term is employed, are always at equal and opposite periodic voltages with respect to ground. Suitable means are provided for utilizing the balanced periodic voltages developed across the impedance means.

In the preferred embodiment of the invention, constant-current devices, such as pentode tubes having suitable potentials applied to their electrodes, are employed as the impedance means, and vacuum tube conductances are employed for controlling the circuits periodically to effect the alternate charge of the capacitance means to

opposite polarities. Suitable means, as for example a regenerating tube, may be provided for accelerating the action of the control tubes. The periodic voltages developed across the impedance means may be applied to scanning plates of a television receiver cathode-ray tube, to effect scanning by the ray.

For a better understanding of the present invention, together with other and further objects thereof, reference is had to the following description, taken in connection with the accompanying drawing, and its scope will be pointed out in the appended claims.

In the accompanying drawing, Fig. 1 is a circuit diagram, partly schematic, of a complete television receiving system including a scanning voltage generator embodying the present invention, while Fig. 2 is a graph of the balanced saw-tooth voltages developed by the generator shown in Fig. 1.

Referring now particularly to the drawing, the system illustrated in Fig. 1 comprises a television receiver, which may be of either the tuned radio-frequency or superheterodyne type, and which includes, in cascade, an antenna and ground system, 10-11, a carrier-frequency amplifier 12, a detector 13, a video-frequency amplifier 14 and a cathode-ray tube 15. Where the receiver is of the superheterodyne type, the conventional oscillator-modulator and intermediate-frequency amplifier will be included as a part of the carrier-frequency amplifier 12. A picture-frequency generator 16 and a line-frequency generator, indicated generally by the numeral 17, are also coupled to the video-frequency amplifier and connected to the scanning elements or plates of the tube 15 in a conventional manner. The generator 17, which is constructed in accordance with the present invention, is shown in detail and will be hereinafter further described. The tube 15 is preferably conventional in construction and operation.

Since the system shown in the drawing, thus far described, is, in general, well understood in the art, a detailed explanation of its general operation is deemed unnecessary. Briefly, however, the vision-modulated carrier waves are intercepted by the antenna 10-11 and selectively amplified in the carrier-frequency amplifier 12. Where the receiver is of the superheterodyne type, the signals will be impressed upon an oscillator-modulator in the amplifier 12 where they will be converted to intermediate frequencies and further selectively amplified. The amplified signal from the amplifier 12 is delivered to the detector 13 in which are derived the video frequencies of modulation including the synchronizing-frequency components which are supplied to the video-frequency amplifier 14, wherein they are amplified and thence supplied, in the usual manner, to the control grid of the cathode-ray tube 15 and to the control elements of the scanning generators 16 and 17. The intensity of the electron beam of the cathode-ray tube 15 is thus modulated or controlled in accordance with the video-frequency voltages impressed on a control electrode of the tube, in the usual manner. The saw-tooth current and voltage scanning waves which are generated in the picture-frequency generator 16 and line-frequency generator 17, respectively, which generators are, as stated, controlled by the synchronizing-voltage impulses supplied from the video-frequency amplifier 14, and are applied to the scanning elements of the cathode-ray tube to produce magnetic and elec-

trostatic fields of saw-tooth wave form, thereby to deflect the ray vertically and horizontally, so as to trace the rectilinear scanning pattern upon the screen and thereby reproduce the transmitted picture.

Referring now more particularly to the portion of the system shown in the drawing which embodies the present invention, the voltage generator 17 comprises capacitance means, more particularly a condenser 18, and a direct-current source, such as a battery 19, by-passed for periodic currents by a suitable condenser 19a, and grounded at its negative terminal, as shown, or any other suitable source of direct current, preferably of negligible impedance to periodic currents. A pair of circuits is provided for charging the condenser 18 to opposite polarities from the battery 19 and means are provided for controlling the circuits periodically to effect alternate charges of the condenser to opposite polarities. Specifically, one of the charging circuits of the condenser 18 includes the control means, preferably comprising two vacuum tubes 20 and 21 of any suitable type connected, as shown, with their space-current paths in series across the battery 19 through the condenser 18 and resistors 22 and 23. Suitable biasing potential is applied to the control grid of the tube 21 from a tap on the battery 19 by way of a resistor 24. The other charging circuit includes impedance means 30 which, in the embodiment of the invention illustrated, comprise two pentode vacuum tubes 32 and 33 having suitable potentials applied from the battery 19, as shown, to their control electrodes so that they operate as constant current 35 devices. Specifically, the constant-current pentodes 32 and 33 are connected with their space-current paths in series across the battery 19 through the condenser 18 and resistors 34 and 35. Suitable potentials are supplied from the 40 battery 19 to the screen grid of the tube 32 by way of a resistor 36 and directly to the screen grid of the tube 33, so that the tubes operate to maintain the current therethrough substantially constant. A large by-pass condenser 43 is connected between the screen grid and cathode of the tube 32 so that the potentials applied to these elements will remain relatively fixed during the operation of the generator and will not be influenced by the periodic current through 45 the impedances which are included in the circuit of this tube. In the preferred embodiment of the invention, the two charging circuits include constant-current devices, as described, and are so proportioned that periodic voltages are 55 developed which are of the same order of magnitude as the voltage of the source 19. Hence the resultant balanced saw-tooth voltage is of an amplitude approaching twice that of the voltage of the source. It will be understood, however, 60 that in place of the constant-current devices, conventional resistance elements may be employed, in which case, in order that good linearity of trace be obtained, the circuit constants are 65 so proportioned that the periodic voltages developed have relatively small amplitudes with respect to the voltage of the source. By virtue of the above-described arrangement, the tubes 32 and 33 are symmetrically disposed in the circuit for the periodic current of the generator. 70

For regenerating the operation of the tubes 20 and 21, there is provided a regenerating tube 25. The input circuit of the tube 25 is effectively coupled to one of the charging circuits of the condenser 18 and to the video-frequency amplifier 14. 75

by connection to the adjustable tap of a voltage divider 26 through a coupling condenser 28. One terminal of the voltage divider 26 is connected to the anode of the tube 20 and the other terminal, 5 through a coupling condenser 27, to the video-frequency amplifier 14. The cathode of the tube 25 is grounded and its control grid circuit includes a suitable biasing resistor 29. The anode of the tube 25 is connected directly to the control 10 grid of the tube 20 and, by way of a coupling condenser 30, to the control grid of the tube 21. Operating voltage is supplied from the battery 19, by way of a resistor 31, to the anode of the tube 25.

15 In order to utilize the periodic voltage thus developed, opposite terminals of the condenser 18 may be connected, by way of coupling condensers 31 and 33, directly to the scanning or deflecting elements of the cathode-ray tube 15. Preferably, a pair of serially-connected resistors 39 and 40 having their junction grounded for 20 periodic currents is connected across the load circuit. The junction of the resistors 39 and 40 may be grounded for direct current also, as 25 shown, or may be maintained at any suitable direct voltage with reference to the operating voltages of the electrodes of the cathode-ray tube.

In considering the operation of the generator 17 shown in the drawing, a single cycle will be described in detail from the point in the cycle at 30 which the condenser 18 is charged to its maximum potential with its upper plate, as shown in the drawing, positive. The tubes 32 and 33 are at all times conductive but the charging circuit 35 of the condenser through these tubes is of high impedance, thereby limiting the rate of charge to a predetermined value. Under these conditions the condenser 18 is gradually and linearly charged, so that the potential of its upper plate 40 increases negatively and that of its lower plate, positively through the circuit commencing at the positive terminal of the battery 19 and including the tube 32, resistor 34, condenser 18, the tube 33 and resistor 35, to the other side of the battery. During this charging operation the potential 45 of the cathode of the tube 32, and thus that of the anode of the tube 21 connected thereto, increases positively, approaching that of the positive terminal of the battery 19. Similarly, the potential of the anode of the tube 33, and thus 50 that of the cathode of the tube 20, increases negatively, approaching that of the negative terminal of the battery 19. This charging action continues until sufficient voltages are built up across 55 the tubes 20 and 21 to break down the tubes to initiate the flow of current therethrough. The initial surge of current results in a voltage impulse across the resistor 22 which is applied 60 negatively to the control grid of the tube 25 by way of the resistor 26 and condenser 28, thereby reducing the conductance of this tube and producing a positive voltage impulse across the resistor 31. This positive voltage is instantaneously applied to the control grids of the tubes 20 and 21, 65 the action of these tubes being thereby regenerated or accelerated, so that current builds up rapidly in the charging circuit which includes these tubes and charges the condenser 18 to the opposite polarity. As the charge of the condenser 70 18 approaches its maximum value of the initial polarity, the charging current is reduced rapidly, with the result that the cathode of the tube 20 rapidly approaches the potential of the positive terminal of the battery 19, while the cathode of the tube 21 rapidly approaches the potential of 75

the negative terminal of the battery 19. Under these conditions, the grid of the tube 20 becomes negative with respect to its cathode by an amount approaching the voltage drop across the resistor 31, while the grid of the tube 20 becomes negative 5 relative to its cathode by an amount approaching the bias impressed thereon from the battery 19 through the resistor 24. The tubes 20 and 21 are thus rendered non-conductive and the charging 10 of the condenser 18 to the opposite polarity is 15 repeated through the tubes 32 and 33, as described above. While the tubes 32 and 33 are at all times conductive, and their circuit is in parallel with the circuit including the tubes 20 and 21, they do not prevent the charging of the condenser 18 through the tubes 21 and 22 to the initial 20 polarity, since the impedance of the circuit including the tubes 32 and 33 is very much higher than that of the circuit including the tubes 20 and 21.

The charging of the capacitance means or condenser 18 alternately to opposite polarities is periodic and the action is synchronized by virtue of the synchronizing impulse voltages which are applied negatively to the control grid of the tube 25 from the video-frequency amplifier, by way of the coupling condenser 27 and voltage divider 26. The circuit constants are so selected that the voltage built up across the tubes 20 and 21 during the trace is just short of breaking down these tubes 30 with normal grid voltages applied. During this portion of the cycle the grid voltage of the tube 25 remains constant so that its anode voltage which is applied directly to the grids of the tubes 20 and 21 is also constant. Upon the occurrence 35 of a negative synchronizing impulse, the conductance of the tube 25 is suddenly decreased and its anode voltage raised. That is, the grid voltages of the tubes 20 and 21 are increased positively to such a value that their existing anode 40 voltages are sufficient to break them down. The effectiveness, on the control of the tube 25, of the synchronizing voltage impulses from the video-frequency amplifier 14 and the voltage developed across resistor 22 may be controlled simultaneously and in opposite senses by adjustment 45 of the tap on the voltage divider. Properly synchronized operation of the generator may thus be obtained. It will be understood that suitable discriminating means will be included in the input 50 circuit of the generator 16 or 17, or both, to ensure that each is controlled only by its respective synchronizing impulses. Since the impedances of the tubes 32 and 33 are of substantially equal 55 values, as are the resistors 34 and 35, and since these elements are symmetrically disposed in their respective charging circuits for the periodic current of the generator, the alternating voltage developed across the condenser 18 is substantially balanced with respect to ground. This voltage 60 is impressed across the resistors 39 and 40 and is applied to the scanning elements of the cathode-ray tube 15, as above described, thereby effecting scanning of the cathode ray with accurate linearity of trace and rapid retrace.

In Fig. 2, curves 41 and 42 represent the voltages developed across the resistors 39 and 40, respectively. In this figure the abscissae represent time and the ordinates represent amplitude. Relative polarities are indicated as + and -, 70 and ground is indicated as 0. The received synchronizing voltage impulses supplied by the video-frequency amplifier determine the frequency of the generator, and the constants of the circuit determine the amplitude of the resultant voltages 75

developed. As clearly shown by the curves 41 and 42, the voltages which are developed are balanced relative to ground.

While there has been described what at present is considered the preferred embodiment of the invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A periodic voltage generator comprising capacitance means, a direct-current circuit, a pair of circuits for charging said capacitance means to opposite polarities from said direct-current circuit, means for controlling said pair of circuits periodically to effect alternate charges of said capacitance means to opposite polarities, one of the circuits of said pair including two impedance means of substantially equal values and symmetrically disposed therein for the periodic current of said generator, and an output circuit in which the periodic voltages developed across said impedance means appear as balanced oppositely poled voltages.

2. A periodic voltage generator comprising capacitance means, a direct-current circuit, a pair of circuits for charging said capacitance means to opposite polarities from said direct-current circuit, means for controlling said pair of circuits periodically to effect alternate charges of said capacitance means to opposite polarities, one of the circuits of said pair including two impedance means of substantially equal values and symmetrically disposed therein for the periodic current of said generator, at least one of said impedance means being adapted to maintain the current in said circuit substantially constant, and an output circuit in which the periodic voltages developed across said impedance means appear as balanced oppositely poled voltages.

3. A periodic voltage generator comprising capacitance means, a direct-current circuit, a pair of circuits for charging said capacitance means to opposite polarities from said direct-current circuit, means for controlling said pair of circuits periodically to effect alternate charges of said capacitance means to opposite polarities, one of the circuits of said pair including two impedance means of substantially equal values and symmetrically disposed therein for the periodic current of said generator, each of said impedance means comprising a constant-current device for maintaining the current in said circuit substantially constant, and an output circuit in which the periodic voltages developed across said impedance means appears as balanced oppositely poled voltages.

4. A periodic voltage generator comprising capacitance means, a direct-current circuit, a pair of circuits for charging said capacitance means to opposite polarities from said direct-current circuit, means for controlling said pair of circuits periodically to effect alternate charges of said capacitance means to opposite polarities, one of the circuits of said pair including two impedance means of substantially equal values and symmetrically disposed therein for the periodic current of said generator, each of said impedance means including the space-current path of a pentode tube, means for applying potentials to the electrodes of said tubes whereby they are effective to maintain the current in said circuit

substantially constant, and an output circuit in which the periodic voltages developed across said impedance means appear as balanced oppositely poled voltages.

5. A periodic voltage generator comprising capacitance means, a direct-current circuit, a pair of circuits for charging said capacitance means to opposite polarities from said direct-current circuit, means for controlling said pair of circuits periodically to effect alternate charges of said capacitance means to opposite polarities, one of the circuits of said pair including two unilaterally conductive impedance means of substantially equal impedance values, said impedance means being symmetrically disposed for the periodic current of said generator, and an output circuit in which the periodic voltages developed across said impedance means appear as balanced oppositely poled voltages.

6. A periodic voltage generator comprising capacitance means, a direct-current circuit, a pair of circuits for charging said capacitance means to opposite polarities from said direct-current circuit, means for controlling said pair of circuits periodically to effect alternate charges of said capacitance means to opposite polarities comprising, in a first of the circuits of said pair, two unilaterally conductive impedance means of substantially equal values, symmetrically disposed therein for the periodic current of said generator and, in the other of the circuits of said pair, two unilaterally conductive means symmetrically disposed therein for the periodic current of said generator and connected with such polarity as to charge said capacitance means to a polarity opposite to that of said first circuit, and an output circuit in which the periodic voltages developed across said impedance means appear as balanced oppositely poled voltages.

7. A periodic voltage generator comprising capacitance means, a direct-current circuit, a pair of circuits for charging said capacitance means to opposite polarities from said direct-current circuit, means for controlling said pair of circuits periodically to effect alternate charges of said capacitance means to opposite polarities comprising, in one of the circuits of said pair, two impedance means of substantially equal values and symmetrically disposed therein for the periodic current of said generator and, in the other of the circuits of said pair, the space-current paths of two vacuum tubes serially connected and symmetrically disposed therein for the periodic current of said generator, and an output circuit in which the periodic voltages developed across said impedance means appear as balanced oppositely poled voltages.

8. A periodic voltage generator comprising capacitance means, a direct-current circuit, a pair of circuits for charging said capacitance means to opposite polarities from said direct-current circuit, means for controlling said pair of circuits periodically to effect alternate charges of said capacitance means to opposite polarities comprising, in one of the circuits of said pair, two impedance means of substantially equal values and symmetrically disposed therein for the periodic current of said generator and, in the other of the circuits of said pair, the space-current paths of two vacuum tubes each having a control electrode, said tubes being serially connected and symmetrically disposed therein for the periodic current of said generator, means for energizing said control electrodes with synchronizing voltage impulses, and an output cir- 75

cuit in which the periodic voltages developed across said impedance means appear as balanced oppositely poled voltages.

9. A periodic voltage generator comprising 5 capacitance means, a direct-current circuit, a pair of circuits for charging said capacitance means to opposite polarities from said direct-current circuit, means for controlling said circuits periodically to effect alternate charges of said capacitance means to opposite polarities comprising, in one of the circuits of said pair, two impedance means of substantially equal values and 10 symmetrically disposed therein for the periodic current of said generator and, in the other of the circuits of said pair, the space-current paths 15 of two vacuum tubes each having a control electrode, said tubes being serially connected and symmetrically disposed therein for the periodic current of said generator, means for energizing 20 said control electrodes with synchronizing voltage impulses, means associated with said tubes for regenerating the action thereof, and an output circuit in which the periodic voltages developed across said impedance means.

25 10. A periodic voltage generator comprising capacitance means, a direct-current circuit, a pair of circuits for charging said capacitance means to opposite polarities from said direct-current circuit, means for controlling said pair 30 of circuits periodically to effect alternate charges of said capacitance means to opposite polarities comprising, in one of the circuits of said pair, two impedance means of substantially equal values and symmetrically disposed therein for 35 the periodic current of said generator and, in the other of the circuits of said pair, the space-current paths of two vacuum tubes each having a control electrode, said tubes being serially connected and symmetrically disposed therein

for the periodic current of said generator, means for energizing said control electrodes with synchronizing voltage impulses, a regenerating vacuum tube amplifier having its input circuit coupled to one of said circuits and its output circuit coupled to the control electrode of at least one of said charging tubes, and an output circuit in which the periodic voltages developed across said impedance means.

11. In a cathode-ray tube television receiver, 10 a periodic voltage generator for developing scanning voltages for the tube of said receiver comprising capacitance means, a direct-current circuit, a pair of circuits for charging said capacitance means to opposite polarities from said direct-current circuit, means for controlling said pair of circuits periodically to effect alternate charges of said capacitance means to opposite polarities, one of the circuits of said pair including two impedance means of substantially equal 15 values and symmetrically disposed therein for the periodic current of said generator, and an output circuit in which the periodic voltages developed across said impedance means.

12. An electric circuit arrangement for developing a periodic voltage balanced relative to ground comprising capacitance means, a direct-current circuit, a pair of circuits for charging said capacitance means to opposite polarities from said direct-current circuit, means for controlling said pair of circuits periodically to effect alternate charges of said capacitance means to opposite polarities, one of the circuits of said pair including two impedance means of substantially equal values and symmetrically disposed therein for 30 the periodic current of said generator, and an output circuit connected across said capacitance means.
